TOOL FOR USE IN PLACES WITH RESTRICTED ACCESS

FIELD OF THE INVENTION

The present invention relates to a tool for tightening and loosening fasteners of the type that include a reaction arm, and in particular to such a tool for use in places with restricted access.

BACKGROUND OF THE INVENTION

Tools are widely used with tightening and loosening fasteners. It is not uncommon for fasteners to be situated within spaces to which access is restricted. Restricted access can make the action of tightening and loosening fasteners difficult, which may result in fasteners not being tightened or loosened correctly, the fastener or surrounding components being damaged or the operator using a tool being required to work in an uncomfortable and inefficient manner. Operators may be injured if a tool were to release from a fastener inadvertently.

One application where access is restricted is in the assembly of aircraft wing components. Where wing components are to be fastened together, access may be so restricted that it is necessary for an operator to climb into the wing in order to position and operate a tool.

Tools that utilise reaction arms can become locked onto the fastener that is being turned by the tool. When this happens removing the tool can be problematic.

Typically, it is not possible to re-position the reaction arm of the above-described type of tool without removing the whole tool from the fastener that is being turned.

It would therefore be desirable to provide a tool that is specifically adapted for use in places in which access is restricted.

It would also be desirable to provide a tool which stops tightening or loosening a fastener once a desired torque has been reached. In the case of aircraft in particular it is important that fasteners are not either over or under tightened.

SUMMARY OF THE INVENTION

According to a first aspect of the invention there is provided a reaction arm mounting assembly comprising a first part and a second part, wherein the first part is configured for attachment to a power tool and a second part is mounted on the first part, and wherein the mounting of the second part on the first part: permits sliding motion between the first and second part along an axis common to the first and second parts in a first sliding region and prevents rotation between the first and second member in the first sliding region; and permits rotation between the first and second members in a second sliding region.

Preferably, the first and second parts of the assembly include co-operating protrusions and indents respectively and wherein the first sliding region is provided by the co-operating protrusions and indents.

Preferably, in the second sliding region one of the first and second parts is free of indents or protrusions that co-operate with protrusions or indents of the other of the first and second member.

It is preferred that, the first part of the reaction arm mounting assembly is free of indents or protrusions in the second sliding region.

One of the first and second parts may be mounted about the other of the first and second parts.

The protrusions and indents may be provided by a plurality of co-operating splines on each of the first and second parts.

The reaction arm mounting assembly may comprise biasing means configured to exert a biasing force on the first and second parts, the biasing force urging the first and second parts biased such that they are situated in the first sliding region.

The assembly may include a biasing means support comprising first and second biasing means support components, wherein the first biasing means support component is attached to the first part and the second biasing means support component is attached to the second part.

A part of the first biasing means support may be surrounded by the biasing means.

The biasing means may be situated inwardly of the second biasing means support component.

Preferably, the first biasing means support comprises a biasing means enclosure member, which surrounds the biasing means and which is arranged to permit sliding and rotation relative to the second biasing means support.

Preferably, the second part forms a part of or is attachable to a reaction arm.

A second aspect of the invention provides a power tool having a reaction arm mounting assembly of the first aspect of the invention attached thereto.

The power tool may further comprise a reaction arm.

Preferably, the reaction arm includes two parts connected together by a lockable pivot assembly.

Preferably, the reaction arm mounts a socket head.

The reaction arm may be adapted for the removable attachment of a socket head.

The power tool may comprise a set of different socket heads.

According to a third aspect of the invention there is provided a power tool including a ratchet drive, the power tool tool comprising:

a ratchet driven socket mounted for rotation within a ratchet drive housing;

a fastener engagement member configured to resist rotation of a fastener engaged therewith;

a mount for the fastener engagement member, the ratchet drive socket, the fastener engagement member and the mount co-axial with each other, the fastener engagement member slidably mounted in the mount, wherein the shape and configuration of the mount and the fastener engagement member prevent relative rotation therebetween;

an opening in the ratchet drive housing, the mount slidably mounted in the opening, wherein the shape and configuration of the mount and the opening prevent relative rotation therebetween;

biasing means arranged to exert a force urging the fastener engagement member along the common axis in a direction away from the opening in the ratchet drive housing;

a motion restrictor associated with the mount and limiting the extent of sliding motion of said mount through the opening.

The motion restrictor may include a first element attached to the mount and at least one second element situated in the path of the mount.

One of the at least one second elements may comprise a collar mounted on the socket and including a portion extending into the path of the first element.

One of the at least one second elements may comprise part of the housing proximate the opening, the first element extending radially beyond the edge of the opening.

The power tool may further comprise a fastener support member including an inner peripheral edge, the fastener so shaped and dimensioned as to permit passage of a fastener therethrough and wherein in use, with a fastener extending through the fastener support member, the inner peripheral edge and an outer surface of the fastener engage with each other upon operation of the power tool.

The power tool may further comprise a cap member attached to the mount and situated to an outer side of the ratchet drive housing, wherein one end of the biasing means is housed in the cap and wherein the cap is provided with means to urge the cap towards the ratchet drive housing.

Preferably, the means to urge the cap towards the ratchet drive housing is a magnetic means.

The magnetic means may comprise a plurality of spaced apart magnets mounted in the cap.

Preferably, the power tool has attached thereto a reaction arm mounting assembly of the first aspect of the invention.

Preferably, the power tool further comprises a reaction arm.

Advantageously, the reaction arm includes two parts connected together by a lockable pivot assembly.

It is preferred that the reaction arm mounts a socket head.

Advantageously, the reaction arm is adapted for the removable attachment of a socket head.

Advantageously, a set of different socket heads is provided for attachment to the reaction arm.

BRIEF DESCRIPTION OF THE DRAWINGS

In the drawings, which illustrate preferred embodiments of the invention and are by way of example:

FIG. 1 is a plan view of a hydraulically actuated tool;

FIG. 2a is a schematic representation of the tool illustrated in FIG. 1 with the reaction arm thereof in a first configuration;

FIG. 2b is an end view of the tool illustrated in FIG. 2a;

FIG. 2c is a plan view of the tool illustrated in FIGS. 2a and 2b;

FIG. 3a is a schematic representation of the tool illustrated in FIG. 1 with the reaction arm thereof in a second configuration;

FIG. 3b is an end view of the tool illustrated in FIG. 3a;

FIG. 3c is a plan view of the tool illustrated in FIGS. 3a and b;

FIG. 4 is a cross-sectional elevation on the axis A-A indicated in FIG. 1;

FIG. 5 is a cross-sectional elevation on the axis B-B indicated in FIG. 1;

FIG. 6a is a schematic representation of a component of the tool illustrated in FIG. 1 view from below;

FIG. 6b is a schematic representation of the component illustrated in FIG. 6a view from above;

FIG. 6c is an end view of the component illustrated in FIGS. 6a and 6b;

FIG. 6d is a cross-sectional elevation of the component on the axis C-C indicated in FIG. 6c;

FIG. 7a is a side view of the hydraulically actuated tool;

FIG. 7b is a section on the axis E-E indicated in FIG. 7a;

FIG. 8 is a schematic representation of components of a hydraulically actuated tool;

FIGS. 9a to 9c illustrate a series of representations of a fastener engagement assembly;

FIG. 10 is a cross-sectional representation of the assembly shown in FIGS. 9a to 9c; and

FIG. 11 is a schematic representation of the assembly shown in FIGS. 9a-9c and 10.

DETAILED DESCRIPTION OF THE PREFERRED EMBODIMENTS

Referring now to FIG. 1, a hydraulically actuated tool 10 comprises a ratchet link 10, a reaction arm 20 and a power head 30.

The arrangement of the components of the tool 1 are illustrated in greater detail in 2a to 11.

The reaction arm 20 is mounted on the ratchet link 10 which comprises spaced apart side plates 11 and a cover plate 12 attached to one of the side plates 11. The cover plate 12 is attached to the side plate 11 by screws 12b. The cover plate 12 includes a plurality of holes 12a which provide for the attachment of a reaction arm mount 14.

The reaction arm mount 14 includes a collar 15 with a flange 15a which includes holes through which externally threaded screws 15b pass to engage with internally threaded holes 12a, thereby attaching the reaction arm 15 to the ratchet link 10.

The reaction arm mount 14 is shown in greater detail in FIG. 5. The collar 15 extends away from the flange 15a and terminates with an internally threaded end 15d. A sleeve 17 has an externally threaded end 17a, the threaded ends 15d and 17a configured such that the sleeve 17 attaches to the collar 15. The sleeve 17 is attached to a cap 14d by means of a screw 17b. A tube 14a is mounted to slide within the cap 14d. A flange 14b extends from one end of the tube 14a and is attached to a first lever 21 of the reaction arm 20 by externally threaded screws 14c which engage with internally threaded holes 21b formed in the lever 21.

A spring 14e is situated between the inner face of the cap 14d and the lever 21. The arrangement of the cap 14d, tube 14a and spring 14e allow the lever 21 to be moved up along the axis x-x against the spring 14e.

FIG. 4 illustrates in detail the arrangement that prevents rotation of the reaction arm 20 relative to the ratchet link 10. The collar 15 mounts a component 16 that includes external teeth 16a. The lever 21 includes an opening 21a, the circumference of which is provided with internal teeth that co-operate with the external teeth 16a of component 16. The teeth may be formed as splines.

The reaction arm mount 14 allows the force exerted on a work piece by the ratchet link 10 to be reacted through the reaction arm 20, and for the position of the reaction arm 20 to be adjusted relative to the ratchet link 10.

To rotate the reaction arm 20 relative to the ratchet link 10 the lever 21 is moved towards the end cap 14d along the axis x-x, compressing the spring 14e until the teeth 21c of the lever 21 are clear of the teeth 16a of the component 16. The reaction arm 20 is then free to rotate about the axis x-x. When the desired position is reached the lever 21 is, if necessary, rotated so the nearest teeth 16a, 21c are aligned. The lever 21 is then allowed to slide relative to the collar 15 until an equilibrium position is reached, that position being determined by the difference in height between the work piece components to which the ratchet link 10 and the reaction arm 20 are attached.

Referring now to FIGS. 2a to 2c specifically, the reaction arm 20 comprises two levers 21, 22 attached to one another for pivoting therebetween. The levers 21, 22 are connected to one another by a pivot assembly 27 which comprises a hole 21d formed in one end of the lever 21, a boss 22a

formed at the end of lever 22, the boss 22 having an internally threaded bore 28b formed therein, a bush 21e pressed into the hole 21d, the boss 22 received in the hole 21d, a knob 28 having an externally threaded screw 29 extending therefrom, and a washer 28a.

To set the angle between the levers 21, 22 the knob 28 is turned so that the threaded end of screw 29 and bore 22b pull the knob 28 towards the boss 22a, compressing the washer 28a between the knob 28 and the upper surface of the lever 21 around the hole 21d. The bush 21e is smaller in diameter than the boss 22a and hence prevents the boss from being pulled through the hole 21d. The knob 28 is tightened such that sufficient friction between the components of the pivot assembly is generated to take up backlash in the reaction arm 20.

To adjust the angle between the levers 21, 22, the knob 28 is rotated so as to slacken off the components of the pivot assembly such that the lever 22 may be rotated relative to the lever 21. The levers 21, 22 are adjusted to a desired position and the knob 28 is re-tightened.

The lever 22 mounts a reaction spanner head 23, which in the illustrated embodiment is a ring spanner 24a mounted in a housing 24. The housing 24 is attached to the lever 22 by a spigot 25 which is received in a corresponding slot 22c. A screw 26 fastens the spigot 25 in position in the slot 22c. Removing the screw 26 allows the spanner head 23 to be changed for an alternative spanner head.

It is not necessary for the knob 28 to be tightened to transfer the reaction force through the reaction arm because the reaction arm is attached to the ratchet drive and component through which torque is reacted in a non-rotatable manner. However, tightening the knob 28 takes up any backlash in the apparatus.

The ratchet link 10 will now be described in greater detail with reference to FIGS. 4 to 8.

The ratchet link 10 comprises a spacer 13 between side plates 11 and a drive plate 140. The drive plate 140 includes a curved nose portion 141 which is acted upon by a piston head 142 which is correspondingly curved so that the two components 141, 142 may slide with respect to one another as the piston 143 reciprocates in cylinder 144 under the influence of pressurised fluid, hydraulic fluid in the present example. In this embodiment the piston 143 is moved in opposing directions in the cylinder by hydraulic fluid pressure, whereas in the embodiment illustrated in FIG. 8 the piston is retuned by a spring 145. The drive plate mounts an externally toothed ratchet socket 150 and drive pawl 16. The ratchet link comprises external teeth 155 which co-operate with teeth 16a of the drive pawl 16. When the drive plate 140 is rotated clockwise the teeth of the drive pawl are forced into the teeth 155 of the ratchet link, causing the fastener engaging element 18a to rotate. On the reverse stroke of the drive plate, in the anti-clockwise direction, the angle of the teeth 155, 16a cause the said teeth to ride over one another. This is facilitated by the manner in which the drive pale 16 is slidably mounted in the drive plate 140, springs 16c biasing the drive pawl towards the ratchet socket 150.

Referring also to FIGS. 9a to 9c in particular, the components of the tool that interact with the fastener in the form of a bolt B and a nut N will be described in greater detail.

In the configuration shown in FIG. 9a, the nut N has been rotated so that the threads thereof are engaged with the threads of bolt B. The bolt B includes a recess B¹ in the upper part thereof. The recess B¹ is hexagonal in the illustrated example. However, other shapes capable of resisting rotation of one part about another may be used. The function

of the fastener engaging element 18a is to prevent rotation of the bolt B as the nut N is fastened onto said bolt. This is achieved by the manner in which the fastener engaging element 18a is mounted on the ratchet link 10.

5 The ratchet link 10 comprises an assembly that both rotates the nut N relative to the bolt B and also holds the bolt B steady. The inner surface of the ratchet socket 150 is provided with fluted peripheral surface shaped and dimensioned to drivingly engage a hexagonal nut N.

10 The fluted surface 156 is best shown in FIG. 8.

An upper region 153 of the ratchet socket 150 mounts a collar 152 for rotation therewith. The collar 152 may be a push fit in the upper region 153 of the ratchet socket 150. The collar 152 includes an inwardly extending wall 154. The 15 function of the wall 154 is to support the whole tool with respect to the bolt B when the nut is relatively tight on the bolt as showing FIG. 9c. At this point the bolt B passes through the opening surrounded by wall 154. It is in this configuration that maximum torque is applied to the nut and 20 bolt. Providing a support in the tool that engages the bolt B steadies the tool on the nut/bolt as torque is applied.

25 A fastener engaging element 18a is mounted slidably in a mounting assembly which comprises a sleeve 18b having an opening 18e therein in which the fastener engaging element 18a is slidably mounted. In the present example the fastener engaging element 18a is hexagonal and the opening 18e is also hexagonal so that relative rotation between the sleeve 18b and the fastener engaging element 18a is not possible.

30 The sleeve 18b is mounted so that it may slide in its axial direction with respect to the ratchet link 10. In particular, the cover plate 12 includes an internally splined opening 12c. The inner peripheral surface of the opening 12c is provided with spines 12. The outer surface of the sleeve 18b is provided with splines 18h which are configured to mate with 35 the splines 12c, thereby permitting movement of the sleeve 18b in the axial direction thereof, whilst preventing rotation of the sleeve 18b relative to the ratchet link 10.

35 A retainer clip 18f is attached to the underside of the sleeve 18b in the clip retaining portion 18b'. The peripheral edge 18g of the clip 18f protrudes radially beyond the edge of the sleeve 18b and is aligned with a recess 12d in the underside of the cover plate 12 adjacent the opening 12c. The retainer clip 18f limits the movement of the sleeve 18b relative to the ratchet link 10.

40 The sleeve 18b is attached to a cap 19 by means of a screw 18d which engages with a threaded hole 18c, the head of the screw 18d sitting in a recess 19d in the cap 19. Hence, the cap and the sleeve 18b are fast with one another for both rotation and axial movement with respect to one another.

45 Referring also to FIG. 9b, as the nut N has been rotated such that the upper face of tool B is proximate the collar 154 and engages with the underside of the sleeve 18b. Further, the spring 19c is fully compressed, the spring 19c being located predominantly in bore 19b of the cap 19. The bore 50 19b is closed at end 19a.

55 Further rotation of the nut N causes the end of the bolt B to push the sleeve 18b upward moving the sleeve 18b axially through the opening 12c in the cover plate 12. As discussed above, the extent of movement of the sleeve 18b is constrained by the interference of retainer clip 18f and recess 12d of the cover plate 12.

60 The cap 19 is provided with four magnets 19e. These magnets secure the cap 19 to the cover plate in the absence of a force sufficient to overcome the force attracting the magnets 19e to the cover plate 12. When the ratchet link is removed from the nut N and bolt B the spring 19c moves the fastener engagement element 18a is moved away from the

cap 19 and the magnets 19e are attracted back into contact with the surface of the cover plate 12.

Operation of the tool is as follows:

- 1) the nut N is placed on the bolt B and the threads thereof engaged manually;
- 2) the socket 150 of the ratchet link is presented up to and mounted on the bolt B;
- 3) the lever arm 20 is raised against the spring force 14e so that the splines 16a and engaging teeth of the lever 21 are clear of one another and the lever arm rotated about the sleeve until the spanner head is aligned with a nut to which the spanner head may be attached;
- 4) the closest corresponding splines and teeth are aligned and the lever 20 slides along the splines 16a;
- 5) the spanner head is attached to the nut with which it is aligned;
- 6) the knob 28 is tightened;
- 7) hydraulic fluid is caused to pass through the power head 30 causing the socket 150 to rotate, tightening or slackening the nut N front the bolt B.

The tool of the invention allows a reaction arm to be attached to an object that lies in a different plane to that of the fastener to which torque is to be applied. Furthermore, the manner in which the reaction arm mounting assembly allows for the reaction arm to be set to a desired angular position relative to the fastener to which torque is to be applied and a component through which the reaction force is to be reacted.

The fastener engagement member provides for torque to be applied to one part of a threaded fastener, for example a nut of a nut and bolt, whilst at the same time preventing a bolt to which the nut is being attached from rotating.

Furthermore, the assembly providing the fastener engagement member may provide a support for the tool during the period where maximum torque is applied to a fastener. The assembly allows the end of a bolt to pass into the ratchet drive as a nut is run down a bolt and a support is provided to engage with the side of the bolt as increasing levels of torque are applied. At the point where maximum torque is applied the ratchet drive may vibrate. Providing a means to support the ratchet drive during such vibration is a significant improvement since unchecked such vibration may result in a ratchet drive coming free from the component being tightened.

The invention claimed is:

1. A power tool including a ratchet drive, the power tool comprising:
  - a ratchet driven socket mounted for rotation within a ratchet drive housing;
  - a fastener engagement member configured to resist rotation of a fastener engaged therewith;
  - a mount for the fastener engagement member, the ratchet drive socket, the fastener engagement member and the mount being co-axial with each other, the fastener engagement member slidably mounted in the mount, wherein a shape and configuration of the mount and the fastener engagement member prevents relative rotation therebetween;
  - an opening extending through the ratchet drive housing, the mount being slidably mounted in the opening and slideable through the opening to be positioned externally of the ratchet drive housing, wherein the shape and the configuration of the mount and the opening prevents relative rotation therebetween;

biasing means arranged to exert a force urging the fastener engagement member along a common axis in a direction away from the opening in the ratchet drive housing; and

- 5 a motion restrictor associated with the mount and limiting an extent of sliding motion of said mount through the opening.

- 10 2. The power tool according to claim 1, wherein the motion restrictor includes a first element attached to the mount and at least one second element situated in a path of the mount.

- 15 3. The power tool according to claim 2, wherein one of the at least one second elements comprises a collar mounted on the ratchet drive socket and including a portion extending into a path of the first element.

- 20 4. The power tool according to claim 2, wherein one of the at least one second elements comprises part of the ratchet drive housing proximate the opening, the first element extending radially beyond an edge of the opening.

- 25 5. The power tool according to claim 1, further comprising a fastener support member including an inner peripheral edge, the fastener support member so shaped and dimensioned as to permit passage of a fastener therethrough and wherein in use, with a fastener extending through the fastener support member, the inner peripheral edge and an outer surface of the fastener engage with each other upon operation of the power tool.

- 30 6. The power tool according to claim 1, further comprising a cap attached to the mount and situated to an outer side of the ratchet drive housing, wherein one end of the biasing means is housed in the cap and wherein the cap is provided with means to urge the cap towards the ratchet drive housing.

- 35 7. The power tool according to claim 6, wherein the means to urge the cap towards the ratchet drive housing is a magnetic means.

- 40 8. The power tool according to claim 7, wherein the magnetic means comprises a plurality of spaced apart magnets mounted in the cap.

- 45 9. A reaction arm mounting assembly comprising a first part and a second part, wherein the first part is configured for attachment to a power tool and the second part is mounted on the first part, and wherein the mounting of the second part on the first part: permits sliding motion between the first and second parts along an axis common to the first and second parts in a first sliding region and prevents rotation between the first and second parts in the first sliding region; and permits rotation between the first and second parts in a second sliding region, and further comprising biasing means configured to exert a biasing force on the first and second parts in a first direction, the biasing force urging the first and second parts to be in the first sliding region, and the biasing force being overcome to move the first and second parts in a second direction opposite the first direction to situate the first and second parts in the second sliding region.

- 50 10. The reaction arm mounting assembly according to claim 9, wherein the first and second parts of the assembly include co-operating protrusions and indents respectively and wherein the first sliding region is provided by the co-operating protrusions and indents.

- 55 11. The reaction arm mounting assembly according to claim 10, wherein the co-operating protrusions and indents are provided by a plurality of co-operating splines on each of the first and second parts.

- 60 12. The reaction arm mounting assembly according to claim 9, wherein in the second sliding region one of the first

and second parts is free of indents or protrusions that co-operate with protrusions or indents of another of the first and second parts.

13. The reaction arm mounting assembly according to claim **12**, wherein the first part of the reaction arm mounting assembly is free of indents or protrusions in the second sliding region.

14. The reaction arm mounting assembly according to claim **9**, wherein one of the first and second parts is mounted about another of the first and second parts.

15. The reaction arm mounting assembly according to claim **9**, wherein the assembly includes a biasing means support comprising first and second biasing means support components, wherein the first biasing means support component is attached to the first part and the second biasing means support component is attached to the second part.

16. The reaction arm mounting assembly according to claim **15**, wherein a part of the first biasing means support component is surrounded by the biasing means.

17. The reaction arm mounting assembly according to claim **15**, wherein the biasing means is situated inwardly of the second biasing means support component.

18. The reaction arm mounting assembly according to claim **15**, wherein the first biasing means support component comprises a biasing means enclosure member, which surrounds the biasing means and which is arranged to permit sliding and rotation relative to the second biasing means support component.

19. The reaction arm mounting assembly according to claim **9**, wherein the second part forms a part of or is attachable to a reaction arm.

20. A power tool having attached thereto a reaction arm mounting assembly comprising a first part and a second part, wherein the first part is configured for attachment to a power tool and a second part is mounted on the first part, and wherein the mounting of the second part on the first part: permits sliding motion between the first and second parts along an axis common to the first and second parts in a first sliding region and prevents rotation between the first and second parts in the first sliding region; and permits rotation between the first and second parts in a second sliding region, and further comprising biasing means configured to exert a biasing force on the first and second parts in a first direction,

the biasing force urging the first and second parts to be in the first sliding region, and the biasing force being overcome to move the first and second parts in a second direction opposite the first direction to situate the first and second parts in the second sliding region.

21. The power tool according to claim **20**, further comprising a reaction arm.

22. The power tool according to claim **21**, wherein the reaction arm includes two parts connected together by a lockable pivot assembly.

23. The power tool according to claim **21**, wherein the reaction arm mounts a socket head.

24. The power tool according to claim **23**, wherein the reaction arm is adapted for removable attachment of a socket head.

25. The power tool according to claim **24**, comprising a set of different socket heads.

26. The power tool according to claim **20**, wherein the power tool includes a ratchet drive, the power tool comprising:

a ratchet driven socket mounted for rotation within a ratchet drive housing;
a fastener engagement member configured to resist rotation of a fastener engaged therewith;
a mount for the fastener engagement member, the ratchet drive socket, the fastener engagement member and the mount co-axial with each other, the fastener engagement member slidably mounted in the mount, wherein the shape and configuration of the mount and the fastener engagement member prevent relative rotation therebetween;

an opening in the ratchet drive housing, the mount slidably mounted in the opening, wherein the shape and configuration of the mount and the opening prevent relative rotation therebetween;

biasing means arranged to exert a force urging the fastener engagement member along the common axis in a direction away from the opening in the ratchet drive housing; and

a motion restrictor associated with the mount and limiting the extent of sliding motion of said mount through the opening.

UNITED STATES PATENT AND TRADEMARK OFFICE
CERTIFICATE OF CORRECTION

PATENT NO. : 11,697,192 B2
APPLICATION NO. : 16/956571
DATED : July 11, 2023
INVENTOR(S) : Stephen Quicke

Page 1 of 1

It is certified that error appears in the above-identified patent and that said Letters Patent is hereby corrected as shown below:

In the Claims

Column 8, Line 13 of Claim 3:
“...second elements comprises...”
Should instead read:
--...second element comprises...--

Column 8, Line 17 of Claim 4:
“...second elements comprises...”
Should instead read:
--...second element comprises...--
